UNITED STATES PATENT OFFICE

161,786

HOUSEHOLD SHELF

Clarence M. Phelps, Grand Rapids, Mich.

Application March 10, 1950, Serial No. 8,455

Term of patent 14 years

(Cl. D33—3)

To all whom it may concern:

Be it known that I, Clarence M. Phelps, a citizen of the United States, residing in Grand Rapids, county of Kent, State of Michigan, have invented a new, original, and ornamental Design for a Household Shelf, of which the following is a specification, reference being had to the accompanying drawing, forming a part thereof.

I claim:

The ornamental design for a household shelf, substantially as shown.

CLARENCE M. PHELPS.
